UNITED STATES PATENT OFFICE.

HENRY A. SCHMIDT, OF MILWAUKEE, WISCONSIN.

DESIGN FOR A CABINET FOR MEDICAL TREATMENT.

SPECIFICATION forming part of Design No. 33,530, dated November 6, 1900.

Application filed September 24, 1900. Serial No. 30,961. Term of patent 7 years.

To all whom it may concern:

Be it known that I, HENRY A. SCHMIDT, a citizen of the United States, residing at Milwaukee, in the county of Milwaukee and State 5 of Wisconsin, have invented and produced a new and original Design for Cabinets for Medical Treatment; and I do hereby declare the following to be a full, clear, and exact description of the same, reference being had to the accompanying drawing, forming a part thereof.

The drawing shows a perspective view of a cabinet embodying my new device.

My design relates to the new and original shape or configuration of the article.

15 The leading or essential feature of my design consists of straight side pieces A A, slightly flared toward the rear of the cabinet and connected by a semioctagonal wall B, the side pieces at the front being connected by doors 20 or panels C, which also form two planes of an octagonal, and are hinged to strips a a, which are continuations of the said pieces A

A. An open top is formed by a band or rim E, starting at the point where the panels C are hinged to the strips a a, and runs rearward 25 to the point b, where it describes a semicircle, as at F, said rim slightly overhanging the sides and rear, the inner edge of which is bent to form a roll d, as shown. The cabinet is also provided at its bottom with feet I at the 30 junction of angles formed by sides, front, and rear, as shown.

Having thus described my invention, what I claim as new, and desire to secure by Letters Patent, is—

35 The design for a cabinet for medical treatment as herein shown and described.

In testimony whereof I affix my signature in presence of two witnesses.

HENRY A. SCHMIDT.
